[57] CLAIM

The ornamental design for a handle for cooking utensil, as shown and described.

DESCRIPTION

FIG. 1 is a top and side perspective view of a handle for cooking utensil, showing my new design;

FIG. 2 is a top plan view thereof;

FIG. 3 is a bottom plan view thereof;

FIG. 4 is a side elevational view thereof, the side opposite being the mirror image thereof;

FIG. 5 is an end elevational view thereof from the right of FIG. 4; and,

FIG. 6 is an end elevational view thereof from the left of FIG. 4.

The small circles represent shallow concave recesses with rounded bottoms.
